UNITED STATES PATENT OFFICE.

FRANK L. KINGSTON, OF CLEVELAND, OHIO.

CARBURETER.

1,156,149.

Specification of Letters Patent. Patented Oct. 12, 1915.

Application filed May 6, 1912. Serial No. 695,425.

To all whom it may concern:

Be it known that I, FRANK L. KINGSTON, a citizen of the United States, residing at Cleveland, in the county of Cuyahoga and State of Ohio, have invented a certain new and useful Improvement in Carbureters, of which the following is a full, clear, and exact description, reference being had to the accompanying drawings.

10. This invention relates to carbureters and has for its main object the simplification of the construction and the cheapening of the cost of manufacture of these devices.

More particularly the objects of the invention may be stated as: the provision of a device of this nature wherein the parts are manufactured so far as possible of metal which is stamped or drawn into shape instead of being cast, thus avoiding the necessity of tedious and expensive lathe work; the provision of a device of this character of great lightness, absolute proof against leakage and reliable and efficient operation; the provision of a new and improved inlet 25 or float valve; the provision of new and improved expedients for rendering the size of the air inlets proportional to the difference in pressure within and without the carbureting chamber; the provision of new and improved expedients for governing the admission 30 of air; while further objects and advantages of my invention will become apparent in the course of the following description and claims.

35. Generally speaking, my invention may be defined as consisting of the combinations of parts defined in the claims hereto annexed and illustrated in the drawings accompanying and forming a part hereof, wherein—

40. Figure 1 is a vertical, central, cross-sectional view through a carbureter constructed in accordance with my invention; Fig. 2 is a horizontal cross-sectional view taken upon the line 2—2 of Fig. 1 and looking downwardly; Fig. 3 is a horizontal cross-sectional view taken upon the broken line 3—3 of Fig. 1 and looking upwardly; Fig. 4 is a detail 45 cross-sectional view through a slightly different form of carbureter, taken on a line corresponding to the line 4—4 of Fig. 3 and looking in the direction of the arrows; Fig. 5 is a perspective view of a portion of the float showing the pivoting and valve operat-

ing means; Fig. 6 is a perspective view of the bracket by which the float is pivoted; Fig. 7 is a perspective view of the clip whereby the float pivot is held in engagement with the bracket; Fig. 8 represents a side elevation of the throttle casing, illustrating the valve operating and adjusting means and the clamp by which the casing is secured to the carbureter body; Fig. 9 is a perspective view of one member of the throttle valve operating means; Fig. 10 is a perspective view of the strangling tube; Fig. 11 illustrates the development of a portion of the air-inlet mechanism shown in Fig. 1; Fig. 12 is a plan view of a modified air-inlet mechanism capable of substitution for that illustrated in Fig. 1; Fig. 13 represents the development of still a third air admission expedient capable of use in the relation shown in Fig. 1; Fig. 14 is a vertical cross-sectional view through the center of a carbureter of slightly different construction, illustrating the application of the air admission expedient shown in Fig. 13; Fig. 15 is a bottom plan view of the carbureter shown in Fig. 14, a portion of the damper-plates being broken away; Fig. 16 is a detail, cross-sectional view on the line 16—16 of Fig. 15; and Fig. 17 is a perspective view of the choking plate or diaphragm.

In general my improved carbureter may be said to consist of an annular fuel reservoir, made in a new manner after a new and improved design, and including new and improved means for maintaining a constant liquid level therein; a tubular chimney defining a carbureting chamber secured within this reservoir and provided with new and improved expedients for the regulated admission of air and fuel thereto; a throttle valve casing; and new and improved means for securing together all of said parts.

Describing the parts by reference characters, 1 represents the inner cylindrical wall of the fuel receptacle and 2 the outer cylindrical wall thereof. This receptacle is preferably formed from sheet brass by drawing the same first in one direction and then in the other, the lower portion of the wall 1 merging with a downwardly flaring portion 3 which in turn merges with the upwardly flaring portion 4, the latter portion being connected at its upper edge with the wall 2.

The height of the wall 1 is preferably greater than that of the wall 2 as illustrated in Fig. 1. The wall 2 is preferably swelled or bulged outwardly at one point in its periphery so as to produce the hollow protuberance 5, said protuberance having an integral substantially horizontal bottom 6 which is punched with a circular aperture for the reception of the fluid supply connection. This connection may conveniently consist of a threaded member 7 adapted to traverse this aperture and having a peripheral flange 8 at its upper end, and also provided with a lock nut 9 whereby it is secured in place.

This member is formed with a longitudinal bore 10 having its upper end flared or otherwise formed as a valve seat, and having its lower end formed for the reception of a nipple 12 adapted to be secured to the member 20 by a gland 13.

Secured in the protuberance 5 is a U-shaped bracket illustrated in perspective in Fig. 6, said bracket comprising a flat bottom plate 14 having an aperture 15 adapted to receive the body of the member 7 and having each of its upright arms 16 formed at its upper end with a vertical notch 17. This plate is clamped against the bottom 6 of the protuberance by the lock nut 9, and in addition the parts 6, 7, 8, 9 and 14 are preferably sweated together with solder. The distance between the outside of the arms 16 is preferably the same as the interior width of the protuberance as illustrated in Fig. 2.

Surrounding the wall 1 of the reservoir is an annular buoyant body 20 of cork or other suitable material, said body having secured to its upper surface at one side the laterally projecting arm illustrated with particularity in Fig. 5. This arm comprises a flat metallic plate 21 having downturned lateral ears 22 for the reception of a pivot wire 23 the ends of which rest in the notches 17-17. Beyond these ears this plate is extended to form a nose 24 bifurcated by means of a slot 25, which slot ends in a slight enlargement 26. The middle portion of the plate 21 between the ears 22-22 and in the rear of the nose 24 is embossed upwardly as shown at 27 for the reception of the shank 28 of a second plate, the forward end whereof is seen at 29, and this forward end is likewise formed with a slot registering with the slot 25 and a recess registering with the recess 26. The rear ends of these plates are secured together by suitable means such as rivets 30 and the whole arm is secured to the body 1 by means of the clenched ends 31 of a suitable staple. The projecting end of this arm forms a point of attachment for the movable member of a valve, said movable member comprising a stem 33 having at one end a conical head 34 adapted to enter the upper end of the bore 10 and having adjacent to but spaced from the upper end an integral spherical enlargement 35. The diameter of the stem 33 is somewhat less than that of the enlargements or recesses 26 and not greater than the width of the slots 25, but the diameter of the enlargement 35 is slightly greater than the distance between the nose 24 and the free end of the plate 29. This construction permits the enlargement 35 to be seated in the enlargement or recess 26 by the springing apart of the plates and be securely retained therein when assembled. The parts can be so designed as to afford the stem the freedom of movement necessary to its proper operation.

The pivot wire 23 is held in the notches 17-17 by means of a U-shaped retaining clip 38 illustrated in Fig. 7, the sides 39-39 of which are spaced apart the same distance as the arms 16-16 of the bracket and are provided with tips 40-40 adapted to enter the notches 17-17 and engage the wire 23.

The top of the reservoir is closed by means of a cover 41, also of sheet brass, and conforming to the shape of said reservoir, said cover having a peripheral downturned flange 42 adapted to overlap the upper edge of the wall 2 and of the protuberance 5. The middle portion of this cover is embossed upwardly as shown at 43 for a purpose which will be described later, and the inner surface of the cover is arranged to engage the clip 38 so as to hold the same securely in place.

Secured within the inner wall of this receptacle is a chimney member which forms the carbureting chamber. The body of this chimney is formed of a tube 45 fitting closely within the wall 1 and extending from a point slightly above the top of said wall to a point intermediate between the top and bottom of the flaring portion 3 where it is flared abruptly outwardly as at 46. The portion 46 merges with an inclined portion 47 the angle whereof is substantially the same as that of the portion 3, and the portion 47 in turn merges with the cylindrical portion 48. Below the portion 48 the wall of this member is formed with a pair of annular stepped shoulders separated by a wall portion 49, and against the upper of these shoulders is clamped the air-inlet device which I shall now explain.

In the embodiment illustrated in Figs. 1 to 12, inclusive, this device consists of a pair of parallel annular metal plates secured together at their peripheries and formed with registering circular apertures spaced about the central aperture, these apertures being provided with upwardly opening valve members whose weights bear different ratios to the sizes of the apertures which they close. In the embodiment illustrated in Figs. 1 to 11 the apertures in the upper plate are of uniform size and the apertures of the lower plate are of varying sizes but all smaller

than those of the upper plate. The lower plate is indicated at 50 and the upper plate at 51, connection between the two being conveniently effected by bending the outer edge 5 of the plate 51 toward that of the plate 50 and wrapping it about the same. The combined edge of these two plates is made strictly circular and formed to fit the smaller of the shoulders above mentioned.

10 At one point the wall 49 is cut away to form an arcuate slot 53, and through this slot projects a radial head 54 here shown as integral with the plate 50. This head is made substantially circular as shown in Fig. 15 3 and is received between the arms 55 of a U-shaped block which is in turn threaded upon an adjusting screw 56. This screw is supported in a rectangular frame 57 secured to the exterior of the carbureter at about 20 the level of the plates 50, 51, in such manner that its rotation will adjust the plates angularly with respect to the mixing chamber. The portion 46 of this member is formed with a plurality of inclined embossed projections 58 conforming in number and arrangement to the apertures above mentioned, and for each pair of apertures is a ball 59 intermediate in size between the apertures in the plate 50 and those in the plate 51. 25 30 In the embodiment illustrated in Figs. 1 and 11 the balls 59 are all of the same size but the fact that they are seated upon apertures of varying size will cause them to be lifted successively upon increase in the pressure 35 of the air, while the rotation of the plates with respect to the fixed inner member of the carbureter will bring these balls beneath the bosses 58 so as to limit the amount of opening movement thereof.

40 - In Fig. 12 I have illustrated a second expedient for accomplishing the same general purpose. In this view I have illustrated a plate 50^a similar in all respects to the plate 50 excepting that the surrounding apertures 45 therein are all of the same size. Secured above this plate is a second plate 51^a similar in all respects to the plate 51 above described with the exception that its apertures are of progressively varying size but concentric 50 with the apertures in the plate 50^a. In the latter apertures and covering the former apertures are valve balls 59^a likewise of progressively varying size, the result being that although the upward force exerted by 55 the air pressure is the same for all apertures, the smallest ball will be the first to rise because of its least weight. The plate 50^a is formed with a central boss 52^a for the reception 60 of the strangling tube and with a radial handle 54^a as before. In each of the above cases the extent of opening of these valves is controlled by rotating the plates which carry the same to different positions beneath the inclines 58.

65 In Figs. 13 to 16 I have illustrated a third

expedient for rendering the area of the air inlet openings proportional to the pressure. In this view I have illustrated the development of a part of a plate 50^b, said plate being similar in all respects to the plate 50 above mentioned, except that instead of being formed with downwardly opening apertures it is formed with a plurality of downwardly depressed or embossed portions 110 each of which takes the form of a shallow inclined ball-receiving groove having at its lowest end a spherical seat 111 in which the ball can snugly fit. These spherical seats are formed with apertures 112, said apertures being of the same size but having axes 80 inclined at varying angles to the plate so that the balls will rest more squarely on some apertures than on other apertures. The balls 59^b being of uniform size, it is obvious that the pressures required to roll 85 them away from their apertures will vary with the directness of application of such pressure with the result that the same will be unseated successively as in the preceding modification. In this embodiment the plate 51 is omitted since the sides of the recesses are sufficient to retain the balls in position, while the amount of opening is limited by rotating the plate beneath the inclines 58 as in the preceding case. 95

The fact that in the device shown in Figs. 1 to 11 the balls are seated in apertures of varying sizes causes them to project to correspondingly varying heights above the plate 50, wherefore the bosses 58 are similarly stepped so that the various balls may be clamped to their seats simultaneously and limited to the same amount of movement. With this construction the balls will rise successively whatever be the limitations of such rising movement. In the device shown in Fig. 12 the varying sizes of the balls cause them to project to unequal heights and necessitate the employment of bosses of varying height. In the modification shown in Figs. 13 to 16, however, the balls project to the same distance above the plate and bosses of equal height are used. These plates may conveniently be secured in place by applying to the shoulder next beneath them a bottom plate 60 having a peripheral flange 61, and crimping inwardly over this flange the edge 62 of the inner member. In the embodiment shown in Fig. 1 this bottom plate is shown as having a downwardly convex body, although this is a matter of design merely, and the middle of this plate is formed with a depending annular flange 63 defining an aperture through which air may be drawn into the mixing chamber. The plate 50 is formed with a hollow upwardly projecting boss 52 surrounding the central aperture thereof and extending through the central aperture in the plate 51, and secured in this boss is what I term the strangling

tube, which consists of a frusto-conical sheet-metal tube 65 having at its larger end a cylindrical portion 66 corresponding in height to the boss 52 and having an annular rib 67 at each end of the said cylindrical portion. One side of this tube is preferably severed from end to end by a slot or scarf 68 which serves to facilitate the contraction of the tube when it is introduced into or removed from the boss 52 as well as having other objects which will be explained later, while the upper end of the tube is formed with a recess 69 with which the slot 68 merges.

15 The inner cylindrical wall 1 of the reservoir and the cylindrical tube 45 of the core are formed with registering inclined apertures 72 at a point opposite to the protuberance 5, and the flaring portion 4 of the 20 reservoir bottom is formed with an aperture 73 in alignment therewith. Mounted in these apertures is a tubular nozzle 74 having its inner end received in the recess 69 of the strangling tube and having its intermediate portion secured in the aforesaid apertures by any convenient means such as will assure a tight joint such as brazing or welding. This nozzle is formed with a constricted portion 75 at a point removed from 25 its inner end so as to define a priming chamber similar to that disclosed in my former patent dated Oct. 25, 1910, No. 974,076, and with internal screw threads at the end opposite said priming cup receiving a needle 30 valve 76 whereby the passage through said constricted portion may be regulated. The outer end of the nozzle tube may be provided with a packing gland 77 to prevent leakage about the valve and to exert sufficient friction thereon to prevent accidental movement. The inner end of the needle valve is reduced as at 78 so as to define an annular chamber which communicates with the interior of the reservoir by means of apertures shown in 35 dotted lines in Fig. 1. The buoyant body 20 is preferably formed with a notch immediately above the tube so as to permit its falling, and the edge of the priming cup is located substantially at but not lower 40 than the normal level of liquid in the reservoir.

The chimney member of the carburetor is secured to the fuel receptacle by flaring outwardly the upper ends of the wall 1 and tube 45 as shown at 80 so as to interlock these portions firmly together at this point and draw the inclined portion 47 of the chimney closely into contact with the flaring portion 3 of the receptacle bottom. The 45 flared portion 80 also forms a seat for the inclined head 81 of the throttle valve casing 82 which head is formed with an annular shoulder 83 at the rear side thereof. Attachment of the casing 82 to the carburetor body is effected by means of a split clamp-

ing ring having an annular abrupt lip 84 adapted to engage the shoulder 83 and an inclined lip 85 adapted to engage the wall 1, the lower face of the clamping ring being disposed with reference to the carburetor 70 body as to cause it to press downwardly upon the raised portion 43 of the cover and lock the same firmly in position. The center of the cover is formed with an aperture 86 of sufficient size to permit the passage of 75 the flaring portion 80, but this aperture is sufficiently closed by the lower face of the clamping member leaving only the necessary venting space.

Journaled inside the casing 82 transversely of its axis is a rock shaft 90 carrying a butterfly valve 91, and secured to the projecting end of this shaft is a sleeve 92 having at its inner end a lateral flange 93. The inner face of this flange is preferably made 80 substantially flat so as to rest against a suitable boss formed on the casing and the outer side thereof is formed with radial serrations 94. Pivoted loosely upon this sleeve is the cylindrical collar 95 of an operating lever 96, one side of which is formed with serrations matching the serrations 94. A cap 97 is threaded to the end of the shaft 90 and locks this lever in adjusting position. The periphery of the flange 93 is formed with 95 spaced radial projections 98 and 99, one of which, as 98, is bent over at its end so as to engage the side of a boss 100 carried by the casing, and the other, as 99, is left straight so as to engage the end of a set screw 101 100 carried by said boss. The object of bending over the projection 98 is to permit it to pass by the head of this set screw as will be apparent by reference to Fig. 8. The arrangement of the projection 98 is such that the 105 throttle valve will be wide open when this projection engages the boss 100, while the position of the projection 99 is such as to permit the closing of the valve to a point which shall just permit the engine to run at 110 its very slowest speed, adjustment of this point for different engines being effected by means of the set screw 101.

For the purpose of holding the valve 91 impositively in position so as to prevent the 115 adjustment of the same from being disturbed by the vibration of the engine, I preferably provide the casing 82 with a recess 105 receiving a spring pressed ball adapted to 120 yieldingly engage suitable notches 106 formed in the edge of the flange 93.

In Figs. 14 to 16 I have illustrated many of my improvements in connection with a carburetor of somewhat different construction. In these views I have illustrated a cast 125 metal receptacle comprising an inner annular wall 1^a, outer wall 2^a, bottom 3^a and protuberance 5^a, the bottom of the protuberance being apertured as before for the reception of a fluid supply connection like that 130

heretofore described. The float, float-valve, and float-valve-supporting-means are the same as those already described, and are likewise secured in place by means of a cover 41 having a downturned peripheral lip 42 and an upwardly bulged portion 43. The upper end of the wall 1^a is illustrated as socketed and threaded as at 120 for the reception of a casing 82^a which may or may not be similar to that before described, and the exterior of said socket portion is outwardly flared as at 85^a for the reception of the similarly beveled lip of a split clamping-ring 84^a, the lower face of which presses 15 downwardly on the cover as in the preceding device.

The bottom of the receptacle is formed with an annular, depending, integral flange 48^a spaced from the inner surface of the wall 1^a and having at its lower end an annular recess 49^a. Seated in this recess is the peripheral lip of the plate 50^b; heretofore described, said plate having a central aperture surrounded by a flange 52^b in which is secured a strangling tube 65 as before. The plane of the plate 50^b is illustrated as raised above the surface of its peripheral lip from the fact that the balls 59^b project above the same a smaller amount than in the other constructions, and the flange 52^b is here shown as downwardly turned because of the greater height of the plate. The inclined bosses 58^a by means of which the opening movement of the balls is limited 35 are here shown as cast directly upon the bottom 3^a of the receptacle, and are made of substantially equal height, inasmuch as the balls 59^b project in all cases substantially equal distances above their plate.

The wall 48^a is formed at one point with a laterally opening arcuate slot 53^a through which projects the arm 54^b which arm is received between the arms 55 of a U-shaped block similar to that previously described 45 and similarly operated. The plate 50^b is secured in place by means of a bottom plate 60 similar to that previously described excepting in having its peripheral flange 61 secured to the wall 48^a by means of a ring 50 62^a attached in place by screws. The fuel nozzle in this case is illustrated at 74^a and is cast integral with the receptacle, but is otherwise exactly like that above described and the passage therethrough is regulated 55 by a needle valve 76 in exactly the same manner. I may also provide means for limiting the amount of air entering the carbureting chamber irrespective as to whether it shall enter through the strangling tube or 60 through the valves surrounding this tube.

In the device shown in Fig. 4 the opening through the flange 63 is totally unimpeded and the total amount of air entering the carbureting chamber can be limited only as far 65 as the capacity of the strangling tube; that

is, although the auxiliary valves may be clamped shut by rotating the plate 50, the strangling tube will always be open.

In some cases, such as on starting the engine in cold weather or when the atmosphere is damp, it is desirable to choke the air inlet to an unusual degree so as to increase the vacuum in the carbureting chamber and temporarily increase the fuel flow. For producing this result I preferably form the plate 60 with segmental damper openings, controllable by means of a rotatable damper-plate, and obstruct the passage through the flange 63 by means of an apertured choking plate, this choking plate being easily removable so as to permit the ready changing of the strangling tube. The apertures in the plate 60 are shown at 125 and the rotatable damper plate at 126, said plate having apertures similar to the apertures 125. The damper 126 is centrally apertured for the reception of the flange 63 and is secured in place against the outer surface of the plate 60 by means of the resilient fingers 127 formed about the periphery of the flat plate or diaphragm 128, said fingers being curved to snap over an annular enlargement 129 formed at the lower end of the flange 63. The plate 128 is apertured at 130 for permitting the access to the carburetor of a minimum quantity of air, the size of this aperture being preferably suited to the peculiarity of the particular engine, and the plate 128 is also formed with an arm 131 whereby it may be rotated. In 100 the embodiment shown herein this arm is illustrated as forming a continuation of one of the fingers 127, although this expedient is obviously a matter of design only, and is formed to engage snugly the face of the damper 126. This arm is formed at a suitable point with a tongue 132 adapted to enter a suitable slot or notch in the damper plate whereby the same may be rotated, and also with a tongue 133 adapted to project 110 through the damper plate and engage the walls of one of the apertures 125 whereby the movement of the damper may be limited to the amount necessary to open and close these apertures. The arm 131 is preferably formed with two tongues 133 as shown in Figs. 15 and 17, so that one of the tongues can be bent inwardly to limit the turning movement of the damper, while the other tongue is left straight, thus enabling 120 the stop to be fixed in such manner as to permit the damper to be rotated in either direction from its closed position as may be necessitated by the particular arrangement of the controlling levers. The damper is 125 formed with suitable slots or notches 134 for the reception of the tongue 133.

It is believed that the operation of the device will be substantially clear from the preceding description of its construction, 130

excepting for a few details of adjustment and operation which will now be pointed out. The nipple 12 being connected to a gasoline supply pipe and the outlet end of the casing 82 to the inlet pipe of an engine, the reservoir will become filled with fluid to a height substantially at or slightly below the level of the lower edge of the inner end of the nozzle 74 when further inflow of fluid 10 will be prevented by the float valve. The passage through the constricted portion 75 of this tube is always open by an amount depending upon the adjustment of the needle valve, so that the priming cup will 15 immediately become filled with fluid, and the air passage through the strangling tube 65 is always open. If now the engine be started in the usual manner, the fuel in the priming cup will be rapidly vaporized by 20 the air rushing through the constricted strangling tube across the mouth of the nozzle tube which thus acts in a manner similar to an atomizer. The size of this strangling tube will vary for different engines, or for 25 the same engine when operating under differing conditions. The elongated slit 68 in the side of the strangling tube not only facilitates its insertion and removal, but permits the admission of a current of air 30 immediately beneath the nozzle tube so as to vaporize any fluid which might run downwardly along the side thereof.

If the engine be cooled or the atmosphere damp so as to require a larger proportion of 35 fuel, the damper 126 is rotated so as to close the air inlet to a greater or less degree, thus increasing the difference in pressure on the exterior of the carbureting chamber and causing an added quantity of fuel to be 40 drawn through the nozzle without changing the adjustment of the needle valve. The aperture 130 limits the closing movement of the air passage and is generally chosen as sufficient to admit the very smallest quantity 45 of air which will cause the operation of the engine. Obviously as long as the amount of air admitted through the plate 60 is less than the capacity of the strangling tube, the balls 59 will remain seated, but as soon as 50 the amount of air admitted past this plate becomes greater than such capacity, the excess will enter through the apertures in the plate 50, (50^a, 50^b) the balls 59 (59^a—59^b) being unseated successively so that the total 55 area of the air inlet will always be approximately proportional to the amount of air demanded.

While I have necessarily described my invention in detail and particularly pointed out the exact features of construction which my experience has indicated as resulting in a particularly efficient, economical, and inexpensive device it is obvious that some of my improvements may be omitted or that other features could be substituted therefor

and many of the advantages I contemplate still realized. It is also apparent that many changes in details and in construction and arrangement of parts could be made without departing from the scope of my invention 70 or avoiding the intent of the claims annexed hereto.

Having thus described my invention, what I claim is:

1. In a carbureter, the combination with 75 an annular reservoir having a cylindrical inner wall, of a chimney member defining a carbureting chamber, said member having a cylindrical tubular extension traversing said inner wall, the upper end of said extension being deflected outwardly so as to interlock with the upper end of the said inner wall.

2. In a carbureter, the combination with 80 an annular receptacle having a cylindrical inner wall, and an outwardly and downwardly flaring portion at the lower end of said wall, of a chimney member having a cylindrical tubular extension traversing said inner wall, and a downwardly and outwardly flaring portion adapted to engage 85 the similar portion of said receptacle, the upper end of said extension being deflected outwardly so as to interlock with the upper end of the said inner wall and draw together 90 said flaring portions.

3. In a carbureter, the combination with 95 an annular receptacle the inner wall whereof projects above the outer wall and has its upper end outwardly flared, of a chimney member secured within said inner wall and 100 defining a carbureting chamber, the upper end of said member being flared into engagement with said first flared portion, a tubular casing having an inclined head projecting into the flaring upper end of said 105 chimney and having an abrupt shoulder, and a clamping ring embracing the abrupt portion of said head and the flaring portion of said wall.

4. In a carbureter, the combination with 110 an annular receptacle the inner wall whereof projects above the outer wall and has its upper end outwardly flared, and an air regulating member secured within said inner wall, of a tubular casing having an inclined head projecting into the flaring upper end 115 of said wall and having an abrupt shoulder, a cover for said receptacle and having an aperture receiving said inner wall, and a clamping ring embracing said head and the flared portion of said inner wall and engaging the top of said cover.

5. In a carbureter, the combination, with 120 an annular receptacle, the inner wall whereof projects above the outer wall and has its upper end outwardly flared, of a tubular casing secured in alinement with said inner wall, a cover for said receptacle and having an upwardly convex top, said cover being formed with an aperture receiving said 125

inner wall, and a split clamping-ring having an inclined portion engaging the inclined portion of said wall and a flat portion engaging the top of said cover, whereby said cover is secured in place and the cover aperture is closed.

6. In a carbureter, the combination, with an annular receptacle, one of whose walls projects above the other wall and has its upper end flared toward said other wall, of a tubular casing secured in alinement with said inner wall, a cover for said receptacle, said cover being formed with an aperture receiving said inner wall, and a clamping member having an inclined portion engaging the inclined portion of said wall and a flat portion engaging the top of said cover, whereby said cover is secured in place.

7. In a carbureter, the combination, with an annular receptacle and means for maintaining a fixed level of fluid fuel in said receptacle, the inner wall of said receptacle defining an air inlet passage, of a straight one piece nozzle tube traversing said receptacle and projecting into said passageway, said tube having a large bore opening through each end and a constricted portion intermediate of its ends, and a valve member adjustably secured in the bore at the outer end of said nozzle tube for governing the passage therethrough, the bore at the inner end of said tube forming a fuel cup.

8. In a carbureter, the combination, with an annular receptacle and means for maintaining a fixed level of fluid fuel in said receptacle, the inner wall of said receptacle defining an air inlet passageway, of a frusto-conical, open-ended tube supported in said passageway with its smaller end uppermost, and a nozzle tube communicating with said receptacle and intersecting said tube near its upper end.

9. In a carbureter, the combination, with an annular receptacle and means for maintaining a fixed level of fluid fuel in said receptacle, said inner wall defining an air inlet passage, of a frusto-conical open-ended tube supported in said passageway with its smaller end uppermost, and an inclined nozzle tube communicating with said receptacle and intersecting said frusto-conical tube near its upper end, said frusto-conical tube having a longitudinal slit in its wall in the same vertical plane with said nozzle tube.

10. In a carbureter, the combination, with an annular receptacle and means for maintaining a fixed level of fluid fuel in said receptacle, said inner wall defining an air inlet passageway, of a frusto-conical, open-ended tube supported in said passageway with its smaller end uppermost, and an inclined nozzle tube intersecting said frusto-conical tube near its upper end and communicating with said receptacle, said nozzle tube having a constricted portion between

said receptacle and its discharge end, said constricted portion being spaced from said discharge end whereby a priming cup is formed, the lowermost edge of said priming cup being not lower than the liquid level 70 and disposed substantially in the vertical axis of said receptacle.

11. In a carbureter, the combination, with an annular receptacle and means for maintaining a fixed level of fluid fuel in said receptacle, the inner wall of said receptacle defining an air inlet passageway, of a frusto-conical, open-ended tube supported in said passageway with its smaller end uppermost, and a fuel nozzle intersecting said frusto-conical tube at an angle near its upper end and communicating with said receptacle, the lowermost edge of the nozzle orifice being not lower than the liquid level.

12. In a carbureter, the combination, with an annular receptacle and means for maintaining a fixed level of fluid fuel in said receptacle, the inner wall of said receptacle defining an air passage, of a plate supported transversely of the lower end of said passage and having a central aperture, an upright tube supported in said aperture, an inclined nozzle tube intersecting said first tube near its upper end and communicating with the interior of said receptacle, and air inlet 95 valves carried by said plate at the sides of said tube and adapted to be opened by the pressure of air thereon.

13. In a carbureter, the combination, with a carbureting chamber, of an upright open tube supported in said chamber, a nozzle communicating with a source of fluid fuel supply and intersecting the upper end of said tube, and means arranged to admit a quantity of air substantially proportional to the difference in pressure existing within and without said chamber, the discharge end of said nozzle being enlarged to form a fuel cup and having its rim disposed obliquely to the axis of said tube.

14. In a carbureter, the combination, with an annular receptacle and means for maintaining a fixed level of fluid fuel in said receptacle, the inner wall of said receptacle defining an air passage, of a nozzle tube 115 projecting from said receptacle substantially to the center of said passage, means for concentrating upon said nozzle the air traversing said passage, a portion of said passage being always open to the admission of air, auxiliary air inlet valves upon the air admission side of said nozzle and adapted to be opened by the pressure of air thereon, and means for adjustably limiting the amount of opening of said auxiliary valves.

15. In a carbureter, the combination, with a carbureting chamber and a nozzle communicating with a source of fluid fuel supply and opening into said chamber, one end of 130

- said chamber being in communication with an inlet connection, of an annular plate traversing said chamber at a point upon the opposite side of said nozzle from said inlet connection and formed with air admission apertures, valve members for certain of said apertures and adapted to admit a quantity of air proportional to the difference in pressure within and without said chamber, and
16. means operative upon all of said valve members simultaneously for adjustably limiting the amount of opening of the same.
16. In a carbureter, the combination, with a carbureting chamber, of a plate closing the lower end of said chamber and having a central aperture and a plurality of air inlet apertures surrounding said central aperture, an upright open tube supported in said central aperture and projecting upwardly into said chamber, and a plurality of valve members for said air admission apertures, said valve members being arranged to open successively upon an increasing difference of pressure within and without said chamber.
25. 17. In a carbureter, the combination, with an open cylindrical carbureting chamber, of an apertured plate closing the lower end of said chamber, certain of said apertures being provided with valve members and other of said apertures being open, said valve members being arranged to open successively upon increase in the difference of pressure within and without said chamber, and guide members for limiting the lateral displacement of said valve members from their apertures.
18. In a carbureter, the combination, with a carbureting chamber, of a plate closing the lower end of said chamber and having a central aperture and smaller apertures surrounding said central aperture, an upright tube secured in said central aperture and projecting upwardly into said chamber, a second plate surrounding said tube and spaced above said first plate and having apertures registering with the surrounding apertures in said first plate, and valve members received in the apertures in said second plate, and resting upon the edges of the apertures in said first plate so as to close the passage therethrough.
19. In a carbureter, the combination, with a carbureting chamber, of a plate closing the lower end of said chamber and having a central aperture and smaller apertures surrounding said central aperture, an upright tube secured in said central aperture and projecting upwardly into said chamber, a second plate surrounding said tube and spaced above said first plate and having apertures registering with the smaller apertures in said first plate, and valve members received in the apertures in said second plate and resting upon the edges of the apertures in
- said first plate so as to close the passage therethrough, the proportion between the weight of said valve members and the size of the surrounding apertures in said first plate varying progressively whereby said valve members will be raised successively from the seats upon an increase in the pressure difference within and without said chamber.
20. In a carbureter, the combination, with a carbureting chamber, of a plate closing the lower end of said chamber and having a central aperture and a plurality of air inlet apertures surrounding said central aperture, an upright open tube supported in said central aperture and projecting upwardly into said chamber, and a plurality of valve members for said surrounding apertures, the proportion between the weights of said valve members and the size of their apertures varying progressively, whereby said valve members will be opened successively upon an increasing difference of pressure within and without said chamber.
21. In a carbureter, the combination, with a carbureting chamber and a fluid fuel nozzle therein, of an apertured plate closing the lower end of said chamber below said nozzle, certain of said apertures being provided with valve members and other of said apertures being open, the ratio of the effective area of said valved apertures to the weights of their respective valve members varying progressively whereby said valve members will be opened successively upon increase in the difference of pressure within and without said chamber.
22. In a carbureter, the combination, with a carbureting chamber, of a plate closing the lower end of said chamber and having a central aperture and smaller apertures surrounding said central aperture, valve members arranged to seat upon said smaller apertures and to be opened successively upon an increase in the pressure difference without and within said chamber, a regulating member above said plate and having portions adapted to engage said valve members whereby the opening movement thereof may be limited, and means for rotating said plate so as to bring said valve members below different portions of said regulating member to adjust the amount of such opening movement.
23. In a carbureter, the combination, with a carbureting chamber, of a plate closing the lower end of said chamber and having a central aperture and smaller apertures surrounding said central aperture, an upright open tube supported in said central aperture, a fluid fuel nozzle opening into said tube, valve members arranged to seat upon said smaller apertures, the ratio of the effective area of said apertures to the weight of

their respective valve members varying progressively, whereby said valve members will be lifted successively upon an increase in the pressure difference without and within said 5 chamber, a regulating member above said plate and having inclined portions adapted to engage said valve members whereby the opening movement thereof may be limited, and means for rotating said plate so as to bring 10 said valve members below different portions of said regulating member to adjust the amount of such opening movement.

24. In a carbureter, the combination, with a carbureting chamber, of a plate closing the lower end of said chamber and having a 15 central aperture and a plurality of apertures of varying sizes surrounding said central aperture, an upright tube secured in said central aperture and projecting freely upward 20 into said chamber, a nozzle communicating with a source of fluid fuel supply and opening into said tube, and a plurality of spherical valve members of equal size and weight closing said surrounding apertures.

25. In a carbureter, the combination, with a carbureting chamber, of a plate closing the lower end of said chamber and having a central aperture and a plurality of apertures of varying sizes surrounding said central 30 aperture, an upright tube secured in said central aperture and projecting freely upward into said chamber, a nozzle communicating with a source of fluid fuel supply and opening into said tube, a plurality of spherical valve members of equal size and weight closing said surrounding apertures, and means retaining said valve members in alignment with their apertures.

26. In a carbureter, the combination, with a carbureting chamber, of a plate closing the lower end of said chamber and having a central aperture and a plurality of apertures of varying sizes surrounding said central aperture, an upright tube secured in said central aperture, a nozzle communicating with a source of fluid fuel supply and opening into said tube, a plurality of spherical valve members of equal size and weight closing said surrounding apertures, a regulating 45 member above said plate and having a plurality of inclined portions equal in number and arrangement to said surrounding apertures, and means for rotating said plate relatively to said regulating member whereby 50 the lifting movement of said valve members may be adjustably limited.

27. In a carbureter, the combination, with a carbureting chamber, of a plate closing the lower end of said chamber and having a central aperture and a plurality of depressions surrounding said central aperture, said depressions having inclined bottoms and the lower ends of said depressions being formed 60 with spherical seats, said seats being formed

with apertures the axes whereof are disposed at different angles as regards the plane of said plate, and spherical valve members resting in said seats and closing said apertures, whereby said valve members will be unseated successively upon an increase in the 70 difference in pressure within and without said chamber.

28. In a carbureter, the combination, with a carbureting chamber, of a plate closing the lower end of said chamber and having a central aperture and a plurality of depressions surrounding said central aperture, said depressions having inclined bottoms and the lower end of said depressions being formed with spherical seats, said seats being formed with apertures, the axes whereof are disposed at different angles as regards the plane of said plate, spherical valve members resting in said seats and closing said apertures whereby said valve members will be unseated successively upon an increase in the difference in pressure within and without said chamber, and a regulating member above said plate and having spaced inclined 80 portions above said valve members, said 85 plate and regulating members being rotatable relatively to each other whereby the opening movement of said valve members is limited.

29. In a carbureter, the combination, with a carbureting chamber, of a plate closing the lower end of said chamber and having a central aperture, a flange surrounding said aperture, an upright frusto-conical tube secured in said aperture, said tube having circumferential ribs overlying the upper and lower ends of said flange, and a nozzle intersecting the upper end of said tube and communicating with a source of fluid fuel supply.

30. In a carbureter, the combination, with a carbureting chamber, of a plate closing the lower end of said chamber and having a central aperture, a flange surrounding said aperture, an upright frusto-conical tube secured in said aperture, said tube having circumferential ribs overlying the upper and lower ends of said flange and an inclined nozzle intersecting the upper end of said tube and communicating with a source of fluid fuel supply, said tube having a longitudinal slit in its wall extending from end to end thereof in the same vertical plane with said nozzle.

31. In a carbureter, the combination, with a carbureting chamber having at its lower end a circular seat, a portion of the wall of said seat being cut away, of a circular plate resting in said seat and having an arm projecting through said slot, said plate having a plurality of upwardly opening air admission valves, a plurality of inclined portions spaced above said valve members,

and means engaging said arm for rotating said plate to bring said valve members under different parts of said inclined portion whereby their opening movement is adjustably limited.

32. In a carbureter, the combination, with an annular receptacle, of a chimney member secured in the opening therethrough, said chimney member having a tubular portion projecting into said opening, a lateral flange below said opening, and a circular seat below said flange, a portion of the wall of said seat being cut away and said flange having a plurality of spaced inclined portions, of a circular plate resting in said seat and having an arm projecting through said slot, whereby it may be rotated, said plate being formed with a plurality of air admission apertures similar in number and arrangement to said inclined portions, and valve members closing said apertures and disposed below said inclined portions, whereby the rotation of said plate will bring said valve members under different parts of said inclined portion to limit their opening movement.

33. In a carbureter, the combination, with a carbureting chamber, of a plate closing the lower end of said chamber and having a plurality of circularly arranged apertures of varying sizes, a plurality of spherical valve members of equal size normally closing said apertures, the diameters of said valve members being greater than that of the largest aperture, and a rotatable regulating member above said plate and having a plurality of inclined portions equal in number and arrangement to said apertures, the arrangement and inclination of said portions being such as to permit all of said valve members to be engaged simultaneously.

34. In a carbureter, the combination, with

a carbureting chamber, of a plate closing the lower end of said chamber and having a plurality of circularly arranged apertures of varying sizes, a plurality of spherical valve members of equal size normally closing said apertures, the diameters of said valve members being greater than that of the largest aperture, and a regulating member above said plate and having a plurality of circularly arranged bosses whose heights vary directly with the diameters of the apertures to which they correspond so that the lift movement of said valve members may be arrested uniformly.

35. In a carbureter, the combination, with a carbureting chamber and a nozzle communicating with the source of fluid fuel supply and opening into said chamber, of a plate traversing said chamber beneath said nozzle and having a plurality of air admission apertures therein, valve members arranged to seat upon the edges of said smaller apertures and close the same, the ratio of the effective area of said apertures to the weight of their respective valve members varying progressively, whereby said valve members will be lifted successively upon an increase in the pressure difference without and within said chamber, and a regulating member above said plate and having stop portions arranged to limit the opening movement of said valve members, the distances of all of said valve members from the corresponding portions of said regulating member being always substantially the same.

In testimony whereof, I hereunto affix my signature in the presence of two witnesses.

FRANK L. KINGSTON.
